UNITED STATES PATENT OFFICE

116,268

DESIGN FOR AN ANIMATED DECORATIVE
LAMP

Aubrey B. Leech, Los Angeles, Calif.

Application March 12, 1938, Serial No. 75,777

Term of patent 14 years

To all whom it may concern:

Be it known that I, Aubrey B. Leech, a citizen of the United States of America, residing at Los Angeles, in the county of Los Angeles and State of California, have invented a new, original, and ornamental Design for an Animated Decorative Lamp, of which the following is a specification, reference being had to the accompanying drawings, forming part thereof.

Fig. 1 is a front elevation of the animated decorative lamp showing my new design and the appearance thereof when the same is illuminated, the successive positions of the drop of blood being indicated in dotted lines.

Fig. 2 is a side elevation of the lamp with the protective housing removed, showing the rotor in place and the base of the electric bulb which causes it to rotate.

Fig. 3 is a front elevation of the lamp taken on the line 3—3 of Fig. 2, showing the intermediate plate which cooperates with the rotor to animate the lamp.

Fig. 4 is a side elevation of the lamp, shown on a smaller scale, with the protective housing in place.

The portions of the rotor and plate which are shown in black are relatively opaque with respect to the balance of the rotor and plate, respectively.

The picture is in colors, the flames being yellow and orange, the heart red, and the background below the heart a buff or tannish color, so that the drops of blood which are red will be clearly visible when the lamp is lit and the rotor moves. The upper drop in Fig. 3 is transparent and the lower drops are colored red on the plate.

I claim:

The ornamental design for an animated decorative lamp, as shown and described.

AUBREY B. LEECH,
